UNITED STATES PATENT OFFICE.

MARGARETTE STORMFELS, OF ALLEGHENY, PENNSYLVANIA.

ENVELOP.

SPECIFICATION forming part of Letters Patent No. 712,465, dated October 28, 1902.

Application filed January 18, 1902. Serial No. 90,242. (No model.)

To all whom it may concern:

Be it known that I, MARGARETTE STORMFELS, a citizen of the United States of America, residing at Allegheny, in the county of Allegheny and State of Pennsylvania, have invented certain new and useful Improvements in Envelops, of which the following is a specification, reference being had therein to the accompanying drawings.

This invention relates to certain new and useful improvements in envelopes, and relates more particularly to that class that cannot be opened without detection.

The present invention has for its object to provide an envelop-blank that will be extremely simple in its construction, strong, durable, and comparatively inexpensive to manufacture; furthermore, to provide an envelop of the above-described character that will be extremely simple in its construction when closed and that will permit the same to be easily opened.

The invention further aims to provide an envelop that when tampered with will leave telltale marks that may be easily discovered.

With the above and other objects in view the invention consists in the novel construction, combination, and arrangement of parts to be hereinafter more particularly described, and specifically pointed out in the claim.

In describing the invention in detail reference is had to the accompanying drawings, forming a part of this specification, and wherein like numerals of reference indicate like parts throughout the several views, in which—

Figure 1 is a plan view of the front of the envelop-blank. Fig. 2 is a front view of the envelop as it appears when the side flaps and lower flap are secured in position. Fig. 3 is a similar view showing the front of the envelop when sealed. Fig. 4 is a detail rear view of the lower flap.

In the drawings the body portion 1 of the envelop carries side flaps 2 and 3, and the lower flap 4 is also a portion of the body portion. The securing-flap 5 extends upwardly from the body portion and has slits 6 formed therein, which extend through the upper edge 50 of the securing-flap. The rear face of the flap 4 is gummed, as indicated at 7, and the

front face of the side flap 3 is also gummed, as shown at 8. The outer face of the slits is also gummed, as indicated at 9.

The manner of folding my improved envelop is as follows: The flap 4 is folded upward and the letter or papers inserted. Then the flap 2 is folded over the flap 4, engaging the gummed edge 7. The flap 3 is then folded over, the gummed edge 8 engaging the flap. The securing-flap is then secured in position, and the envelop is securely sealed.

It will be noted that various changes may be made in the details of construction of my improved envelop without departing from the general spirit of my invention.

Having fully described my invention, what I claim as new, and desire to secure by Letters Patent, is—

In an envelop, the combination of a body portion carrying an imperforate lower flap having its rear face gummed, imperforate side flaps carried by the body portion with one of said side flaps having its front face gummed, a securing-flap having its front face gummed and having a series of slits therein extending through the upper edge of said flap forming a series of independent tongues, the lower flap being folded upwardly into position and having a portion of its rear gummed face engaged by the front face of the un-gummed side flap, the remaining portion of the said gummed face of the lower flap being engaged by the front face of the other of said side flaps, the gummed face of said last-named side flap engaging the rear face of the first-named side flap, the side flaps engaging and extending onto the upper portion of the lower flap throughout the length thereof, both of the rear faces of the side flaps being engaged by said independent tongues on the securing-flap which are received directly upon said rear faces of the side flaps and which have their outer faces entirely exposed, substantially as described.

In testimony whereof I affix my signature in the presence of two witnesses.

MARGARETTE STORMFELS.
